US0D1076894S

(12) **United States Design Patent** (10) **Patent No.:** **US D1,076,894 S**
(45) **Date of Patent:** **** May 27, 2025**

(54) **ANTENNA**

(71) Applicant: **Avery Dennison Retail Information Services LLC**, Mentor, OH (US)

(72) Inventor: **Abed Pour Sohrab**, Chelmsford (GB)

(73) Assignee: **Avery Dennison Retail Information Services LLC**, Mentor, OH (US)

(**) Term: **15 Years**

(21) Appl. No.: **29/921,050**

(22) Filed: **Dec. 14, 2023**

(51) LOC (15) Cl. **14-03**

(52) U.S. Cl.

USPC **D14/230**

(58) **Field of Classification Search**
